United States Patent Office

Des. 227,525
Patented July 3, 1973

227,525

DISPLAY CASE FOR A COIN OR THE LIKE

James R. Skinner, Cupertino, and Mark O. Uitz, Mountain View, Calif., assignors to M. U. Engineering & Mfg., Inc., Mountain View, Calif.

Filed June 1, 1971, Ser. No. 149,104

Term of patent 14 years

Int. Cl. D6—99

U.S. Cl. D6—172

FIG. 1 is an isometric view of the display case for a coin or the like showing our new design;

FIG. 2 is a front elevational view thereof;

FIG. 3 is a top plan view thereof;

FIG. 4 is a left end elevational view thereof;

FIG. 5 is a right end elevational view thereof; and

FIG. 6 is a bottom plan view thereof.

We claim:

The ornamental design for a display case for a coin or the like, as shown.
